UNITED STATES PATENT OFFICE.

RUDOLF HENNIG, OF HAMBURG, GERMANY, ASSIGNOR TO GEBR. PAGLOW, OF
KL. GRASBROOK, NEAR HAMBURG, GERMANY.

DEVICE FOR STARTING AND SCAVENGING TWO-CYCLE ENGINES.

1,259,398

Specification of Letters Patent. Patented Mar. 12, 1918.

Application filed October 20, 1915. Serial No. 57,021.

To all whom it may concern:

Be it known that I, RUDOLF HENNIG, a subject of the German Emperor, and resident of Hamburg, Germany, have invented certain new and useful Improvements in Devices for Starting and Scavenging Two-Cycle Engines, whereof the following is a specification.

The present invention refers to a device for starting and intensified scavenging by means of a scavenging pump in two stroke cycle engines, the object being to arrange the parts so that there will be a minimum consumption of compressed air when starting; furthermore to feed the scavenging air, compressed by the scavenging piston, by avoiding large spaces for its accumulation, as directly and as completely as possible to the working cylinder through ports or passages having a minimum volume so as to obtain by this an intensified scavenging of the working cylinder for the purpose of increasing the output.

By means of the hitherto known arrangements of scavenging pumps in two cycle engines this result cannot be attained.

The scavenging pumps of two cycle engines are, as a rule, provided with admission organs (suction valves, flaps, slides, ports and the like) and with exhaust organs of a similar construction. The feeding of the scavenging air is effected from the scavenging pump to a special receptacle or a piping of comparatively great capacity wherein the scavenging air is stored under moderate pressure.

In engines in which scavenging air is compressed in the crank case as is common in single acting engines, the exhaust organ of the scavenging pump is constituted by ports in the working cylinder, which ports are positively opened by the working piston when the same reaches the end of the explosion stroke. In this case the crank case forms a voluminous compression space and has to be especially packed at its joints to prevent leakage.

Furthermore, it is customary in both cases to employ a check valve in the passage from the crank case to the intake port of the cylinder to prevent the products of combustion finding their way into the crank case and thus contaminating the scavenging air.

It is furthermore known that by means of

these check valves a so-called prolonged scavenging may be attained, because the admission ports are at the least as long as or longer than the exhaust ports, whereby an increased quantity of air can be supplied to the working cylinder and thereby an increased output be obtained.

Finally, when the scavenging pump is employed for starting the engine with compressed air, on account of the large spaces existing in the two first named devices, considerable quantities of compressed starting air are required.

According to the present invention the results mentioned at the beginning of this specification are attained in a simple and efficient manner by giving the delivery valves of the scavenging pump the form of non-return or check valves and at the same time that of shut-off valves when starting the engine with compressed air, in which design the crank of the piston of the scavenging pump is displaced with regard to the cranks of the working pistons in such a manner that a small consumption of starting compressed air and an intensified positive scavenging of the working cylinder with pure scavenging air and with a minimum of loss is rendered possible. For the purpose of obtaining a further reduction of the consumption of compressed air, it is advantageous to give the passages from the scavenging pump to the engine cylinder the least possible dimensions and to arrange the exhaust valves as near to the scavenging air cylinder as possible.

The object of the present invention is schematically shown by way of example in the drawing, in which—

Figure 1 shows the cylinders in vertical longitudinal section.

Fig. 2 shows the corresponding horizontal section of the same.

Fig. 3 is a sectional view of a check valve used herewith in closed position.

Fig. 4 is a similar view with the valve gear.

Fig. 5 is a diagrammatic view showing the device for admitting starting air and for operating the mechanism which holds the check valves closed.

As Fig. 1 shows, the two working cylinders V_1 and V_2 of the two stroke cycle engine are provided with single acting plungers T_1 and T_2 and arranged on both sides

of the scavenging air cylinder S, comprising a double acting piston D. The three cylinders form a united casting. Furthermore a_1 , a_2 and e_1 , e_2 are the exhaust ports and the admission ports respectively of the working cylinders.

The scavenging air cylinder is provided with the ports g , through which (in case of a correct working of the engine) the outer 10 air enters and through which, when starting is effected by compressed air, the exhaust air is exhausted in known manner (see also Fig. 2).

From the scavenging air pump two upper 15 ports o_1 , o_2 and two lower ports u_1 , u_2 , lead to the admission ports e_1 , e_2 of the working cylinder. In these ports four check valves are mounted, which valves open toward the admission ports e_1 and e_2 respectively.

20 Each of these check valves comprises a stem e surrounded by a sleeve f having a head f^1 at one end forming a seat for a valve spring m . This head fits in the end of a cup-shaped valve b_1 having a flange at its 25 open end arranged to fit a respective valve seat.

The devices k_1 , k_2 between the valves are intended for the purpose of pressing said check valves b_1 , b_2 , when the engine is started, 30 down upon their seats and to release them when the engine is running. At the same time they serve the spring plates of these valves as supports when said valves are released. The devices k_1 , k_2 may, as is shown 35 in Fig. 2, be simultaneously turned by means of levers and rods, whereby the rollers r_1 , r_2 are lifted from the valves or pressed against the same. Furthermore the devices k_1 , k_2 partially fill the objectionable spaces 40 in the ports e_1 , e_2 , said spaces being preferably of reduced dimensions.

Each of these devices k_1 and k_2 consists of a rotatable disk u whereon are journaled the rollers r_1 and r_2 .

45 The handle h is pivoted on a fixed pin h^1 and engages with its free lower end a tubular cam shaft splined on a valve operating shaft v . On this cam shaft are cams q and q^1 which are adapted to engage the stems of 50 valves i_1 , i_2 , i_3 and i_4 when the cam shaft is moved to the right or left, but when the cam shaft is in its central position, the cams are free from the valve stems as shown in Fig. 5. These valves remain closed while, at the 55 same time, the check valves are free to open so that the engine works in its normal manner. The tube w is in communication with a reservoir containing compressed air, while the tubes w_1 , w_2 , w_3 and w_4 lead the compressed air to the four cylinders V_1 , V_2 , D and S of the engine.

The three driving cranks of the pistons are set at 90° as shown at 1, 2 and 3 in Fig. 1.

For a good operation of the engine it is 65 essential that the objectionable spaces o_1 , o_2

and u_1 , u_2 of the scavenging air pump be very small as compared to the corresponding working volume of the scavenging pump (preferably about 5% thereof) and also the objectionable spaces adjoining the ports e_1 , e_2 70 should be small as compared to the working volume of the cylinders V_1 , V_2 .

For the purpose of starting the engine forward or backward the handle h is moved to the left or to the right respectively. By 75 this movement the cams q or q^1 respectively are brought in line with the spindles of the valves i_1 , i_2 , i_3 and i_4 , and one of the valves is opened by the corresponding cam. If the parts of the engine before starting have the 80 position shown in Fig. 1, the valve i_3 or i_4 is opened by operating the handle h . Said handle turns also the devices k_1 , k_2 in such a manner, that the rollers r_1 , r_2 hold the check valves b_1 and b_2 closed. 85

As soon as the engine has reached the necessary speed, the handle h is brought into the position shown in Fig. 5, the fuel is conveyed to the engine and the normal working of the latter begins. 90

The normal operation of the engine is as follows:

When the crank 3 is about 60° in front of its lowest position the piston T_2 opens the ports a_2 and e_2 . As soon as the pressure of 95 the exhaust gases has become less than the pressure of the air compressed by the downward stroke under the piston D, the lower valve b_2 is lifted and the compressed air streams through the cylinder V_2 . Prior to 100 the opening of the ports a_2 and e_2 the scavenging air piston D moving upward has shut the ports g and has compressed the air over itself. Therefore the upper valve b_2 opens sometime after the lower valve b_2 , and the 105 air compressed over the piston D passes through the cylinder V_2 until the piston T_2 again shuts the ports a_2 and e_2 .

The remainder of the air compressed above the piston D serves for accelerating the 110 scavenging of the cylinder V_1 by entering, through the top valve b_1 , this cylinder after its exhaust, similarly to the action above described with reference to the air below the piston D passing into the cylinder V_2 . 115

What I claim as my invention and desire to secure by United States Letters Patent is:—

1. In combination, a two-cycle engine having a cylinder, an air pump, a conduit for conveying air compressed by said pump to scavenge the cylinder of said engine, a check valve located in said conduit, said valve having an adjustable spring plate, means for starting the engine by compressed air, and a 120 device for pressing said spring plate against said valve to close positively said valve during the starting.

2. In combination, a two-cycle engine having a crank shaft provided with cranks at 125

- right angles to each other, and a piston connected to one of the cranks of said shaft, an air pump having a piston connected to the remaining crank, a conduit for conveying air compressed by said pump to scavenge the cylinder of said engine, a check valve located in said conduit, said valve having an adjustable spring plate, means for starting the engine by compressed air, and a device for pressing said spring plate against said valve to close positively said valve during the starting. 5
3. In combination, a two-cycle engine having a cylinder, an air pump, a conduit of small volume leading from said pump to the cylinder of said engine for conveying compressed air to scavenge said cylinder, a check valve located in said conduit, said valve having an adjustable spring plate, means for 10 starting the engine by compressed air, and a device for pressing said spring plate against said valve to close positively said valve during the starting. 15
4. In combination a two-cycle engine having a pair of cylinders, an air-pump located between said cylinders, conduits for conveying air compressed by said pump to scavenge each of said cylinders, a check valve located in each of said conduits, said valve having an adjustable spring plate, means for starting the engine by compressed air, and a device for pressing said spring plate against said valve to close positively said valve during the starting. 20
5. In combination, a two-cylinder two-cycle engine having a pair of pistons, a crank shaft having a pair of cranks arranged at 180° and a third crank at 90° to the others, connections between the pistons and the pair of cranks, an air pump located between said cylinders and having a piston connected to the third crank, conduits for conveying air compressed by said pump to scavenge each of said cylinders, a check valve located in each of said conduits, means for starting the engine by compressed air, and means for positively closing said valves during the starting. 25
6. In combination, a two-cycle engine having a pair of cylinders, an air-pump located between said cylinders and having a piston adapted to compress air on both sides thereof, conduits of small volume leading from each side of said piston to each of said cylinders for conveying air compressed by said pump to scavenge each of said cylinders, a check valve located in each of said conduits, means for starting the engine by compressed air, and means, simultaneously operative with the starting means, for positively closing all of said valves during the starting. 30

In testimony whereof I have signed my name to this specification in the presence of two subscribing witnesses.

RUDOLF HENNIG.
